INVENTOR.

Thomas R. Post,
BY R. N. Gullus

ATTORNEY.

UNITED STATES PATENT OFFICE

THOMAS R. POST, OF WILMINGTON, NORTH CAROLINA

COTTON-PICKER SUCTION TUBE

Original application filed November 13, 1926, Serial No. 148,242. Divided and this application filed April 16, 1927. Serial No. 184,333.

This invention relates to cotton pickers and has special reference to a division of my prior application for patent on cotton picker, filed November 13, 1926, Serial Number 5 148,242, abandoned and refiled February 23, 1928, Serial No. 256,457. My said application 15 256,457 relates to general pneumatic picker structure.

More particularly the invention relates to 10 a gathering head for cotton picker suction tubes.

The principal object of the present invention is to provide an improved and novel construction of gathering head for the suction 15 tubes of cotton pickers, the head being so arranged that it may operate effectively in any position to remove the cotton from the squares.

With the above and other objects in view 20 as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a side elevation of the cotton 30 picker suction tube showing the gathering head thereon and the means for manipulating the same.

Figure 2 is an enlarged detail view of 35 the gathering head or mouth and disclosing the swivel arrangement, the view being partly in section.

Figure 3 is a bottom plan view of the part shown in Figure 2, this view being likewise partly in section.

In the present disclosure the same general 40 type of machine is employed as that disclosed in the previous application above referred to, only certain parts of that machine being here shown. Of these parts there is disclosed a 45 standard 23 having in its upper end a ball socket 24 wherein rests a suitable ball held in the socket by a cover plate 26 provided with a suitable opening through which passes the shank 28 of said ball. This shank 28 supports a U-shaped frame 29 provided with

spaced pairs of bearing rollers between which is supported a conveyor tube 31 which bends at its forward end at right angles, the bent portion 32 lying normally in a horizontal position and being provided with a flange 33 55 which bears against a flange 34 formed on an elbow 35 having an open mouth end 36. The flanges 33 and 34 are held together by a cover plate 37 and thus the mouth can swivel on the right angular portion 32 and, as seen 60 in Figure 1, can be inclined forwardly or rearwardly at will. This forward and rearward movement is controlled by the operator through the medium of an arm 38 fixed to the elbow flange 34 and connected by a rod 39 65 with a lever 40 pivotally mounted on an operating arm or handle 41 which projects upwardly from the tube 31 in front of the operator's position. Thus by grasping the arm 41 with the left hand and the lever 40 with the right 70 hand the operator is enabled to move the tube forwardly or rearwardly, swing it in any direction, and tilt it up and down. I may also incline the mouth in any direction by rotating the tube 31 by manipulating the handle 41. 75

It will be observed that there is provided a blast pipe or tube 22 adapted to be connected by a flexible pipe 21 with a suitable blower and that this pipe 22 is provided at its forward end with a return bend 43 which connects with a nozzle member 44 arranged on the bend 32 axially of the pipe 31. By this means when the blower is operated a forcible jet of air is blown into the forward end of the tube 31 and sets up a heavy suction in the 85 mouth 36 in the usual manner. Furthermore, this mouth 36 is provided with a series of light fingers 45 which are pivoted at 46 to the periphery of the mouth and are inclined normally inwardly of said mouth. These 90 fingers are held from too great movement toward the opening of the mouth by stop members 47 and are pressed toward said opening by light springs 48. By this means, when the mouth is dropped over a boll by the operator, the cotton is engaged by the points of the fingers and if the suction itself is not sufficient to draw the cotton out of the square or boll the mouth may be lifted which will effectively remove the cotton. Owing to the in- 100

clination of the fingers and the ease with which they move inwardly, the suction will then strip the cotton off the fingers and the air jet will carry it back through the pipe 31. 5 The rear end of the pipe 31 is connected by a flexible tube 49 to the ginning mechanism as described in the aforesaid prior application.

There has thus been provided a simple and 10 efficient device of the kind described and for the purpose specified.

It is obvious that minor changes may be made in the form and construction of the invention without departing from the material 15 spirit thereof. It is not, therefore, desired to confine the invention to the exact form herein shown and described, but it is desired to include all such as properly come within the scope claimed.

20 Having thus described the invention, what is claimed as new, is:

1. In a cotton picker of the pneumatic type, a cotton boll engaging mouth piece, a series of light yieldable fingers extending 25 radially inward from the wall of the mouth and inclined rearwardly from the opening of said mouth, hinge connections between the outer ends of said fingers and said wall, and stop lugs to limit the movement of the inner 30 ends of the fingers toward the opening of the mouth.

2. In a cotton picker of the pneumatic type, a cotton boll engaging mouth piece, a series of light yieldable fingers extending radially 35 inward from the wall of the mouth and inclined rearwardly from the opening of said mouth, hinge connections between the outer ends of said fingers and said wall, stop lugs to limit the movement of the inner ends of 40 the fingers toward the opening of the mouth, and light springs interposed between the fingers and said wall and urging the inner ends of the fingers toward said opening.

In testimony whereof I affix my signature.

45 THOMAS R. POST.
